WATERCRAFT

Tony Naginskas, Chicago, Ill.

Application May 28, 1938, Serial No. 210,568

6 Claims. (Cl. 115—37)

The present invention relates to a particular type of watercraft so designed as to make for the maximum of efficiency.

The main and primary object of this invention is to improve that portion of a watercraft which is below the surface level of the water to enable such craft to acquire the maximum of speed with given motive power.

Another object is the provision of a design or shape which is in agreement configuratively with the shape of a fish and has for its object propulsion thru water by virtue of the physical principles residing in the shape or structure of a fish.

A further object of the invention is to provide a series of propellers so mounted as to accentuate the effect of the water pressure on the side of the craft and impel the same in a forward direction.

Another object of the invention is to have secondary propeller means in order to neutralize the turbulent action caused within the water pressure stream so as to obtain the maximum efficiency from the primary propellers provided for imparting motion to the craft.

Other and further objects may become apparent by reference to the accompanying drawing, and description where like symbols are used to designate like parts and where;

Fig. 1 represents a front plan view of that portion of my invention which is submerged below the surface of the water.

Fig. 2 is a bottom plan view of my invention as shown in Figure 1.

Fig. 3 is a transversal cross-sectional view on the line 3—3 of Figure 1.

Fig. 4 is a longitudinal cross-sectional view on the line 4—4 of Figure 3.

By referring to the drawing Figure 1 and Figure 2 generally show that portion of my water craft which is submerged below the water and resembling in shape a fish.

The craft generally designated by the numeral 8 is provided with a rudder portion in the shape designated at 9 and which is suitably hinged by the hinge member 10 to the main body of the craft 8. This craft 8 is provided with a suitable means of motive power, such as gasoline engine, Diesel engine, or any suitable marine engine which motive power is connected by virtue of its two extended shafts 6 thru suitable bearings designated by 7 and 7' to the propeller structures designated by 13 and 14 respectively.

In looking at Figure 2 it will be noticed that the rudder portion swings at the tail end in like manner as the tail of a fish moves, the means

for rotation, however, being provided by a hinge member. Further examining Figure 1 we notice that there are two side fin members designated by the numeral 11, and by referring to Figure 2 it will be noticed that they are streamlined in accordance with the shape designated by 12.

The fins 11 furnish the general housing for the propellers and the mechanism needed to drive the propellers 13 and 14 in the directions indicated. It will be noticed that the propellers 13 respectively operate in opposite directions and the propellers 14 on either side of the craft operate in opposite directions. The respective structure on any one side rotates the propeller 13 in the opposite direction to the propeller 14 on the same side, in other words the propeller 13 on one side of the craft is rotating in the same direction as the propeller 14 on the opposite side of the craft, and vice versa.

To describe further the mechanism required in order to obtain this opposite direction of rotation with respect to the propellers 13 and 14 reference is to be had to Figure 3 and Figure 4. In Figure 3 we notice a fragmentary sectional view of the fin member generally designated by 11 and which has a cavity designated by the numeral 28, which houses the main portion of the mechanism needed to transmit this opposite rotation to the propeller members.

The side of the boat or craft 8 has mounted thereon the bearing 7 and said bearing is made up of two halves, equipped with the flanges 17 which are clamped to the inner and outer sides of the boat 8 by means of clamp screws 16 and clamp nuts 15. These bearings 7 house the driving shaft 6 operated by the motive power 5, and this shaft 6 is connected to a bevel gear 18, and connected to the same by the pin 19, which makes the gear 18 integral with the driving shaft 6. The bevel gear 18 is meshed with the bevel gear 20 at right angles to it, the bevel gear 20 being mounted on the hollow shaft 29 which has a reduced shoulder portion 23 to fit the bevel gear 20, and is held in place by a set screw designated by the numeral 21. This hollow shaft has a recess to receive packing 27 and the fin 11 has a hub portion 24 which is to receive the packing nut 25 which furnishes a gland to prevent leakage of the water into the mechanism within the fin.

The structure is further reinforced against leakage by the gasket member 26 which is clamped tightly between the boss provided on the fin and the clamping nut member 25. The hub 24 has a hole 22 to provide a running fit for the hollow

shaft 29. The upper portion of the hollow shaft 29 has a hub 30 with recesses 31 into which are fitted respectively the propeller members 13 and keyed or pinned by virtue of the pins 32 to be held tightly and securely in place. This hollow shaft member further upward has a recess to receive gland packing 33 and receives an assembly of the shaft member 46 which has a housing 34 arranged in a like manner to receive a smaller set 10 of propeller blades designated by the numeral 14 and keyed by virtue of pins or keys 35 in like manner as the propeller blades designated 13 are secured respectively to the hollow shaft 29.

The housing 34 is pinned to the shaft 47 by 15 virtue of pin 36. This shaft 46 can be seen extending all the way thru the hollow shaft 29 and attached to the bevel gear 37 by a pin 41, the shaft 46 clearing straight thru the hollow shaft 29. The bevel gear 37 meshes with another 20 bevel gear at right angles thereto designated by the numeral 40. The spur gear 39 mounted integrally with the bevel gear 40 meshes with the intermediate spur gear pinion 47 which in turn meshes with an internal ring or annular gear 25 designated by 38, mounted in such a manner as to rotate freely within the clamping ring designated by the numeral 42', the said clamping ring being secured to the bottom of the fin 11 by the screws and nuts 43'.

30 The clamping ring 42' has a recess 45 which is to receive a shoulder 44 on the annular ring gear 38 in order to permit it to rotate freely under the said holding ring member 42' without lifting out of meshing engagement. The gears 39 and 35 40 are rotatably mounted on studs 43 whereas the gear 47 is mounted on the stud 42. The annular ring gear 38 is also provided with bevel gear teeth on its outer periphery so as to mesh with the gear 20.

40 The shaft member 6 turns integrally with the bevel gear 18 which meshes with the gear 20 and provides rotation with the hollow shaft 29 holding the propeller blades 13, which may be considered as right handed when looking at Figure 45 3.

45 By the arrangement shown in Figures 3 and 4 it will be noticed that when the shaft 6 rotates away from the observer the gear 20 rotating in the same direction, will rotate the annular gear 38 which by virtue of internal teeth 49 will rotate 50 the pinion 47. The pinion 47 rotates the spur gear 39 integrally mounted with bevel gear 40, which in turn meshes with the bevel gear 37 hence producing rotation of the propeller blades 14 in a left handed direction of rotation or opposite to 55 that of the propeller blades 13.

In like manner the direction of rotation is respectively reversed with respect to the opposite fin member assembly so that as heretofore explained the secondary or small propeller on the one side 60 will rotate in the same direction of rotation as the larger or primary propeller on the opposing side.

It will be noted that the propeller assemblies are mounted at a slight angle to the shaft 6, in 65 other words on a center line parallel to the tapered end of the craft 3. The reason for this being to direct the propelling lines of force created by the propellers rearward and inward toward the craft, providing a pushing action at 70 the stern or rear of the craft.

The operation of the craft and advantages are as follows:

Assuming that the boat, by means of the propeller and the motive power, is moved in a forward direction as viewed in Figure 2 the nose or

75 prow of the craft in cutting thru the stream will tend to create a pressure stream which will be forced toward the tapered rear end or stern of the craft and by being forced against the tapered stern will have a tendency to accentuate the forward propulsion of the craft. When the water craft is propelled forward the nose or the prow of the submerged part of the craft designated by the numeral 48 tends to create lines of force which open outward and slide along the front 10 portion of the prow tending, as it were, to create a vacuum at the rear portion or tapered end of the craft which draws the lines of force or pressure so generated so that when they strike the tapered side or portion of the boat the waves have 15 a tendency to impel the boat or craft in a more forceful manner.

The waves so generated are further accentuated in their action by the primary propeller blades heretofore designated by 13 which rotate 20 and are so shaped as to force the water tangentially to the tapered section 3 of the water craft and which have a resulting effect of impelling the boat in a forward direction. The secondary or smaller propellers designated by 14 are provided 25 in order to receive the lines of force created by the waves generated by the nose 48 breaking thru the water and which tend to produce a general turbulent effect. The propellers 14 confine the lines of force so generated to one plane of action 30 namely the horizontal plane resulting in concentration of the force of propulsion to most effectively propel the craft forward. The propellers 13 turning each in an opposite direction insure stabilizing the craft. 35

The two sets of propellers are mounted one on each side to provide equilibrium to the craft eliminating the gyration which might be caused by propellers turning in the same or one direction. The rudder being in the same shape as the tail 40 of a fish is operated in a similar manner as the rudder on any standard craft in order to provide a change of direction with respect to the prow of the craft.

I believe I have explained in succinct terms 45 the nature and advantages of my particular type of water craft, so those skilled in the art may find it understandable and quite explicit. Altho I show a specific embodiment or construction I wish it understood that I reserve the right to such 50 changes, modifications and alterations that come within the purview of the description, the accompanying drawing and the subjoined claims.

Having thus described my invention what I claim as new and desire to secure by Letters 55 Patent is:

1. A surface craft comprising, a completely submerged hull portion shaped configuratively to resemble the shape of a fish, provided with hollow streamlined fin portions located on each side of the said hull portion approximately midway between the front and rear of said hull, and adapted to house gearing transmission means, also provided with suitable motive power means mounted within the said hull portion, and propeller means 60 mounted on each side of the said craft adapted to be rotated thru said gearing transmission means in order to propel the craft in a horizontal plane. 65

2. A surface craft comprising, a completely submerged hull portion shaped configuratively to resemble the shape of a fish, provided with hollow streamlined fin portions located on each side of the said hull portion approximately midway between the front and rear of said hull, gearing transmission housed therein, also pro- 70 75

- vided with suitable independent motive power means adapted to drive the gearing in each of said fin portions, mounted within the said hull portion, a hinged rudder structure, and propeller means mounted toward the prow on each side of the craft to stabilize the same, said propeller means comprising a primary propeller and a secondary propeller to intensify the propelling action of the said primary propeller, the respective primary propeller on one side of the craft rotating oppositely to its secondary propeller, and in an opposite direction to its mated primary propeller on the other side of the craft, said propeller means adapted to be rotated by said gearing transmission means in order to propel the craft in a horizontal plane. 5
3. A surface craft comprising, a completely submerged hull portion shaped configuratively to resemble the shape of a fish, provided with hollow streamlined fin portions located on each side of the said hull portion approximately midway between the front and rear of said hull, and adapted to house gearing transmission means, also provided with suitable motive power means mounted within the said hull portion, a hinged rudder structure mounted at the rear of the craft, and propeller means mounted on an axis of rotation approximately parallel to the tapered side of the stern of the craft and adapted to be rotated thru said gearing transmission means in order to propel the craft in a horizontal plane. 10
4. In a surface craft, the combination with motive power means and propeller means, of a completely submerged hull shaped configuratively to resemble the shape of a fish, provided with hollow streamlined fin portions, gearing transmission means housed therein, comprising a driving bevel gear meshing with a driven bevel gear fixed to a hollow propeller shaft, a second propeller shaft journaled in said hollow propeller shaft having a bevel gear attached thereto, an annular bevel gear adapted to mesh with the bevel gear secured to said hollow propeller shaft, also provided with internal spur gear teeth, and three intermediate gears adapted to reverse the direction of rotation of the hollow propeller shaft with respect to the said second propeller shaft. 15
5. In a surface craft, the combination with motive power means and propeller means, of a completely submerged hull shaped configuratively to resemble the shape of a fish, provided with hollow streamlined fin portions, gearing transmission means housed therein, comprising a driving bevel gear meshing with a driven bevel gear fixed to a hollow propeller shaft, a second propeller shaft journaled in said hollow propeller
- shaft having a bevel gear attached thereto, an annular bevel gear adapted to mesh with the bevel gear secured to said hollow propeller shaft, also provided with internal spur gear teeth, and three intermediate gears adapted to reverse the direction of rotation of the said hollow shaft with respect to the said second propeller shaft. 20
6. In a surface craft, the combination with motive power means and propeller means, of a completely submerged hull shaped configuratively to resemble the shape of a fish, provided with hollow stream-lined fin portions, gearing transmission means housed therein, comprising a driving bevel gear meshing with a driven bevel gear fixed to a hollow propeller shaft, a second propeller shaft journaled in said hollow propeller shaft having a bevel gear attached thereto, an annular bevel gear having external bevel gear teeth adapted to mesh with the bevel gear secured to the said hollow propeller shaft, the said annular bevel gear also provided with internal spur gear teeth, an intermediate spur gear in mesh with the internal teeth of said annular bevel gear, a compound gear structure comprising a spur and bevel gear secured integrally, the said compound gear structure having its spur gear in mesh with the said intermediate spur gear and having its bevel gear in mesh with the bevel gear secured to the said second propeller shaft, the said annular bevel gear further provided with a retaining bead, and an annular retaining ring rigidly secured to the base of said fin portion, the said retaining ring adapted to secure rotatably the said annular bevel gear, the said annular bevel gear, the said intermediate spur gear, and the said compound gear structure adapted to reverse the direction of rotation of the said hollow propeller shaft with respect to the said second propeller shaft. 25
